UNITED STATES PATENT OFFICE.

GEORGE L. BUCKLEY, OF HARLAN, IOWA.

CORN-PLANTER.

SPECIFICATION forming part of Letters Patent No. 663,008, dated December 4, 1900.

Application filed October 10, 1898. Serial No. 693,153. (No model.)

To all whom it may concern:

Be it known that I, GEORGE L. BUCKLEY, residing at Harlan, in the county of Shelby and State of Iowa, have invented certain useful Improvements in Corn-Planters; and I do hereby declare that the following is a full, clear, and exact description thereof, such as will enable others skilled in the art to which it appertains to make and use the same, reference being had to the accompanying drawings, which form a part of this specification.

This invention has relation to a new and novel improvement in corn-planters.

The object of my invention is to provide a corn-planter which shall be noticeable because of its simplicity of construction and operation and in which the operating parts shall be readily accessible and adjustable.

In the accompanying drawings, Figure 1 shows a top view, with portions broken away, of a corn-planter embodying my invention. Fig. 2 shows a side elevation of a corn-planter embodying my invention with portions broken away. Fig. 3 shows a side elevation of one of the runners, showing the connected seed-feeding mechanism with parts broken away, while Fig. 4 shows a detached detail, with portions broken away, of the revolving plate within the seed-reservoir. Fig. 5 shows a cross-sectional view forward of shaft C. Fig. 6 shows an enlarged view with portions broken away, disclosing the arrangement of the tilting tube as used in my invention.

My invention embodies, essentially, a rectangular frame comprising the side sills 2 2, the end connection 1, the transverse bar 4, and the extending transverse sill 3, secured to the forward portion of the sills 2 2. This frame is provided with an ordinary axle pivoted with the wheels a a' , as is usual in machines of this class.

Each forward sill 2 is bifurcated, so that the ears 32 of the frame K, which forms the main stay of the runner-frame, and which runner-frame is provided with the tongue 35, to which is secured at its forward end a cross-bar 36, from which cross-bar 36 extend rearward the usual runners or shoes F' F', the frame being strengthened by the diagonal pieces 34 34. From this it will be seen that my invention embodies a rear wheeled frame which is piv-

otally secured to a forward runner-frame, which forward frame is provided with the tongue to which the draft-animals are secured.

Pivots positioned within the rear edge 55 of the vertical chutes of the runners F' are the oscillating tubes D, which below terminate above a shelf 38 within the runner, and which shelf 38 acts as a bottom for the tube D when said tube is in one position. A suitable distance above the pivot-point of these tubes D they are slotted, so as to permit the entry of a shelf 37, as is shown in Figs. 1 and 3 of the drawings, which shelves 37 divide them into two compartments. In referring 60 to the drawings it will be noticed that the shoe F' is provided with the slot, which permits the vibration of the tube D.

Secured to the upper portion of each shoe is a plate B, which is flush with the top of 70 the tube D, and to which plate B is secured an ordinary housing L, forming the seed-reservoir, within the bottom of which is a perforated feed-plate 56, as is usual, which permits the seed to enter the tubes D. 75

Pivots secured to each base-plate B is a lever 25, pivoted by means of the pin 28, and to the shorter end of which is pivotally secured a bar 29, which bar 29 is again movably secured to the tube D, so that as this lever 25 is reciprocated the tube D is vibrated in such a manner that the seed which falls through the tube D is first lodged upon the shelf 37, from which it is swept by means of the oscillation of the tube so as to fall downward and lodge upon the shelf 38, mentioned as being within the shoe below this tube and shown in Fig. 3, and from this shelf the seed is again swept by the oscillation of the tube and permitted to enter the furrow. From 90 this it will be noticed that there are always two charges of seed within the tube D, one being upon the upper shelf 37 and the other upon the shelf 38 below the tube D.

The hopper mechanism permitting the feeding of the seed to the tube D may be of any suitable construction.

In Fig. 4 a perforated plate 56 is shown having suitable openings 57, within which the seed would lodge, and this plate 56 is provided with a ratchet 58, which is actuated by means of a pawl 26, secured to the lever 25,

so that this lever not only rocks the tube D, as is shown in Fig. 1, but simultaneously rotates the plate 56 to successively bring the seed-holding openings 57 above the tube D.

5 Journaled within the upwardly-extending brackets c c is a shaft 17, which upon one side projects beyond the brackets and is provided with a pulley 16, over which works an ordinary chain 10, which chain further works 10 over a pulley 9, which pulley is revolubly mounted upon the axle 8 and has a clutch-face which is adapted to engage the clutch-face b of the wheel a'. An ordinary spring 12 normally forces these two clutch-faces into 15 engagement. The pulley-section 9 is provided with an upwardly-extending flange 11, which flange is engaged by the downwardly-extending portion 15 of the foot-lever 14, which lever is pivoted to one of the sills 2 by means of a suitable pin 13. As long as 20 the clutch-pulley 9 is in engagement with the wheel a' the shaft 17 is revolved; but this shaft can be instantly thrown out of engagement 25 by means of the foot-lever 14.

25 Journaled within the sills 2 2 is a transverse shaft C, which is provided with an upward extension 22, which extension is bifurcated at its upper end, and between which bifurcation is held a shaft 21, which projects 30 beyond the extension 22 and to the ends of which are secured the rods 24 24, which rods by means of the pins f are secured to the levers 25, as shown. The spring 23 normally exerts a pressure to draw this extension 22 forward.

35 Secured to the shaft 17 is a wheel A, which wheel is provided with the curved outward extensions or projections 20 20, which are adapted to engage the shaft 21 to impart a downward motion to the extension 22, the 40 spring 23 immediately drawing back this extension 22 as soon as the shaft 21 escapes the projections. This movement of the extension imparts a rocking motion to the levers 25 to 45 actuate the tubes D. It might here be stated that the levers 25 are provided with spring-actuated pawls 26, adapted to rotate the feed-plates within the seed-reservoirs.

Mounted upon each side of the wheel A upon the shaft 17 is a disk 54, provided at 50 suitable points with a tooth-section 55, and adjacent to these teeth are the projecting pins 53, as is shown in Fig. 1.

Secured to the sills 2 2 are the inwardly-extending brackets 50, which are provided 55 with the stub-shafts 49, supporting the double gears F, which gears are provided with the integral bevel-gears 51, the double gears F being further provided with the projecting piece i, so arranged that the peripheral 60 edge of each disk 54 rides within a seating of these gears F until the pin 53 engages the guide-piece i, when the gear-wheels F are given approximately one full revolution. By this mechanism it will be noticed that a continuous rotary motion of the disks 54 imparts an 65 intermittent rotary motion to the pinions F.

To the transverse bar 3 are secured the up-

wardly-extending brackets 46, within which brackets work the stub-shafts 47, which shafts also work into the bearings 49, as is shown in 70 Fig. 1. Each of these stub-shafts is provided with a chain-pulley 45 and a bevel-gear 48, the bevel-gears meshing with the bevel-gears 51. The bar near each end is provided with a transverse stub, upon one side supporting 75 the revolving marker 40 and upon the opposite side a pulley 41, a chain 43 passing over the pulley 41 and the pulley 45. Now should the main shaft 17 be actuated by the wheel a' the disks 54 would impart an intermittent 80 rotary motion to the pinions F, and so to the shafts 47, to revolve the markers 40, which would make a mark in the earth transversely to the path of the machine, showing just where the seed had been deposited. Simultaneously with the action of the marker the extension 22 would have actuated the connecting-levers to oscillate the tubes D to receive and deposit the seed. The usual marker 7, secured to the rod 6, is here employed journaled to the rear cross-bar of the frame. 85

From this it will be noticed that my invention is simple of construction and readily operated, and,

Having thus described my invention, what 95 I claim as new, and desire to secure by United States Letters Patent, is—

1. The combination with a wheel-supported frame, of a runner-frame pivotally secured thereto, seed-reservoirs secured to said runner-frame, seed-feeding mechanism within said reservoirs, an oscillating tube below said seed-feeding mechanism, said tubes being slotted above, a shelf entering said tubes near the upper end, a shelf below said tube near the lower end, a lever to oscillate said tube, and mechanism to oscillate said levers, as and for the purpose set forth.

2. The combination with a wheel-supported frame, of a drive-shaft journaled in said frame, belt connection between said drive-shaft and one of said supporting-wheels, a supported stub-shaft, partially-toothed disks secured to said drive-shaft, suitably-supported mutilated gears working in conjunction with said disks and said stub-shaft connecting said drive-shaft to said stub-shaft to intermittently rotate said stub-shaft, a supported marker revolving in a plane at right angles to the path of said wheel-supported frame, 115 and belt connection between said marker and said intermittently revolving shaft to intermittently impart a rotary motion to said marker.

3. The combination with a wheel-supported frame, of a forward runner-frame pivotally secured to said wheel-supported frame, runners secured to said runner-frame, seed-reservoirs secured to said runners, seed-feeding mechanism within said reservoirs, a pivoted lever actuating said seed-feeding mechanism, a rock-arm secured to said pivoted lever, a drive-shaft in belt connection with one of said supporting-wheels, a disk upon said shaft 125 130

provided with projections adapted to engage said rock-arm, partially-toothed disks upon said drive-shaft, a pinion adapted to receive the peripheral edge of said partially-toothed disks to be intermittently rotated by said disks, and a supported marker rotating at right angles to the path of said wheel-supported frame in belt connection with said mu-

tilated gear, all arranged substantially as and for the purpose set forth. 10

In testimony whereof I affix my signature in the presence of two witnesses.

GEORGE L. BUCKLEY.
